United States Patent Office

Des. 208,985
Patented Oct. 24, 1967

208,985

GOLF BAG

Howard J. Wilkens, Cincinnati, Ohio, assignor to Brunswick Corporation, Chicago, Ill., a corporation of Delaware

Filed Nov. 10, 1966, Ser. No. 4,619

Term of patent 14 years

(Cl. D34—5)

FIG.3

The dominant features of the design are shown in full lines on the drawing.

I claim:

The ornamental design for a golf bag, as shown and described.
